CLAIM

(57) The ornamental design for an outsole cover, as shown and described.

DESCRIPTION

FIG. 1 is a side perspective view of an outsole cover showing our new design;

FIG. 2 is a top plan view thereof;

FIG. 3 is a first side elevational view thereof;

FIG. 4 is an opposite side elevational view thereof;

FIG. 5 is front elevational view thereof;

FIG. 6 is back elevational view thereof; and,

FIG. 7 is a bottom plan view thereof.

The broken lines in FIG. 7 represent the boundary of the design. The broken lines form no part of the claim.

1 Claim, 5 Drawing Sheets---
